UNITED STATES PATENT OFFICE.

FRANK B. COLMAN, OF NEW YORK, N. Y.

ELECTRICALLY-ACTUATED VIBRATOR.

SPECIFICATION forming part of Letters Patent No. 367,270, dated July 26, 1887.

Application filed November 23, 1886. Serial No. 219,633 (No model.)

To all whom it may concern:

Be it known that I, FRANK B. COLMAN, of New York city, State of New York, have invented certain new and useful Improvements 5 in Electrically-Actuated Vibrators, of which the following is a specification.

In some systems of telegraphy, now generally known, automatic vibrators are employed, and the signals are reproduced either upon a telephonic receiver or otherwise by throwing upon the line groups or a succession of vibratory impulses divided to correspond to dots and dashes of the Morse alphabet. Where the receiver employed is an ordinary speaking-telephone, 10 it is desirable to employ in connection with it a transmitting-vibrator having a high pitch and a keen distinct sound, so that when it is thrown into and out of vibration sharply-defined signals are produced in the telephonic 15 receiver. A vibrator of such a character gives better results than the ordinary tuned reeds or strings tuned to musical tones.

In the now well-known Phelps' system of induction telegraphy, it has been proposed to 20 employ vibrators in connection with speaking-telephone receivers for the purpose above mentioned. My improved instrument is designed more especially for use in connection with that system; but it is not confined to such 25 a use, and may be employed wherever an electric vibrator is needed.

In the accompanying drawings, which illustrate the invention in a practical and efficient form, Figure 1 is a side elevation of the adjusting-nut in section, with one or two minor parts broken away or in section. Fig. 2 is an 30 end view partly in elevation and section; Fig. 3 a plan view, and Fig. 4 a detail view, of the vibrator, magnet, and adjusting devices, with 35 the parts of the frame removed.

A is a bed-plate, of any suitable material, having two uprights, *a a*, preferably connected by a cross-piece, *b*. Beneath the cross-piece *b* a string-bar vibrator, *C*, is shown in suitable 40 proximity to the poles of a magnet, *M*. The vibrator *C* may be secured in place at one end by engaging a lug or stud, *a'*, upon one of the uprights of the cross-piece *b* in an aperture in the bar. The opposite end is connected with 45 the hooked end of a rod, *D*, passing loosely through an aperture in the upright *a*. The outer end of the rod is screw-threaded and is

provided with an adjusting-nut, *d*, and between the hub of the adjusting-nut and the upright *a* is interposed a stout coiled spring, *s*. 55 By screwing up the nut, therefore, an elastic strain or tension may be put upon the string-bar. If desired, the rod *D* may be clamped rigidly by a set-screw, *E*, working in a hub in the upright *a*. By this construction the string-bar may be strained to any desired tension, 60 and the tone which it will give out when vibrating may therefore be modified as required. So far as this part of my invention is concerned it is not limited to a string-bar vibrator, but it applies to electric vibrators of different forms. For instance, if the vibrator shown were widened, the result would be the same, and if such a widened vibrator were supported continuously along its edges and 65 held under elastic tension the result would be the same. This invention therefore contemplates no limit as to shape or form, but comprehends, in its broadest terms, an electric vibrator of any description which is held under 70 an elastic or yielding tension. In this connection I am of course aware that electric vibrators of various kinds have been provided with means for straining them to produce the tone or number of vibrations desired, and I do 75 not claim such subject-matter.

A bridge, *F*, straddles the cross-piece *b* and carries a contact-screw, *G*, which passes through an aperture in the cross-piece and works in a socket in a split block, *g*, on the bridge *F*. The 80 parts of the split block *g* may be rigidly clamped against the screw by a screw-bolt, *H*, working in threaded sockets in the divided block and arranged transversely to the contact-screw *G*. This device is not new in itself and is not 85 broadly claimed herein. It is, however, of special advantage in the particular use to which it is here applied, as the contact-screw *G* may be adjusted with great delicacy relatively to the platinum contact on the vibrator, 90 and may then, by means of the clamping-bolt *H*, be firmly clamped in exactly the position to which it has been adjusted.

With the ordinary check-nut there is liability of error, because the contact is moved a distance equal to the slack in the thread of the screw when the check-nut is screwed up.

The circuit is from one binding-post, *X*, through the magnet *M M* to the contact-screw

G, vibrator, and other binding-post Y, and when a circuit through the magnet M is completed by the closing of a key or any transmitting device the vibrator will be thrown 5 into action and will automatically make and break the circuit at the contact G, as usual.

As the vibrator is liable to become heated by sparking at the contacts and also by reason of mechanical impact against the contact-screw, there is a tendency for it to elongate, thus modifying its rate of vibration and the sound emitted by it and reproduced in the telephonic receiver. To compensate for such a possibility, a series of small apertures is punched or 15 formed in the vibrator, preferably around or near the contact thereon. These apertures serve to take up the expansion of the metal at this point and prevent any disturbance of the normal rate of vibration, and as the radiating- 20 surface is increased the bar cools more rapidly.

Should any further adjustment be desired other than that afforded by the manipulation of the adjusting-nut d, it may be obtained by lengthening or shortening the vibrator. This 25 may be accomplished in the following manner: A link or stirrup, I, arranged on either or both sides of the bridge F, embraces the cross piece b and the vibrator, and is provided on its upper side with a clamping-screw, which passes 30 through the link and bears against the cross-piece b. A block of metal is loosely interposed between the vibrator and the under side of the cross-piece b, and by screwing up the bolt i the vibrator may be firmly clamped be- 35 tween the block i' and the bottom of the link or stirrup. As these links may be moved along the cross-piece b to any point desired, the length of the reed may in effect be changed and its tone or number of vibrations per sec- 40 ond increased or diminished. As before re- marked, one only of such adjustable clamps may be used, or two if desired, one on each side of the magnet M.

It is immaterial what means are resorted to 45 to effect the movement of the link on the cross-piece b. The arrangement may be such as illustrated in the drawings, in which the adjustment is effected by merely loosening the clamping-bolt and moving the link and block 50 by hand; but any other manner of adjustment, whereby a greater nicety or accuracy of adjustment could be obtained, may be adopted.

So far as I am aware I am the first to pro- 55 vide clamping devices in connection with a string-bar vibrator supported at both ends, whereby the bar may in effect be lengthened or shortened to modify its rate.

As usual in electric vibrators, I prefer to 60 mount the magnet M so that it can be ad- justed toward or from the vibrator, and the manner in which I prefer to effect this ad- justment is as follows: The magnet M is car-

ried by a disk, M', screw-threaded on its outer periphery and surrounded by a screw-threaded collar or ring, M². The disk is perforated on 65 opposite sides, and through these perforations bolts, which screw into the bed-plate, loosely pass. By revolving the ring M', therefore, the disk carrying the magnet may be raised and lowered. By screwing down the bolts 70 H² the parts are firmly locked or clamped.

I claim as my invention—

1. The combination of an electrically-actuated vibrator with elastic or yielding ten- 75 sion devices for straining it.

2. The combination of a string-bar confined at both ends, an elastic or yielding tension device for straining said bar, and an electro- 80 magnet for vibrating it.

3. The combination of a vibrating bar sup- 85 ported in a frame at both ends, a magnet for vibrat- ing it, the adjusting-rod D, the adjust- 90 ing-nut, and the spring.

4. The combination of a vibrating string- 95 bar supported at both ends, a magnet for vi- 100 brating it, and a clamping device between its ends, adjustable lengthwise of the string-bar, to increase or decrease its vibratory length, substantially as set forth.

5. The combination of the vibrator sup- 105 ported at both ends, a magnet for actuating it, elastic or yielding tension devices for strain- 110 ing the bar, and clamping devices for clamp- 115 ing the bar between its ends to increase or diminish its vibratory length, substantially as set forth.

6. The combination of an electrically-act- 120 uated vibrator having apertures formed there- 125 in, and a contact against which the vibrator 130 works, whereby the expansion due to heating 135 of the vibrator is taken up, substantially as set forth.

7. The combination of a string-bar vibrator 140 confined at both ends and having apertures 145 formed therein, a contact on the vibrator in proximity to said apertures, an opposite con- 150 tact against which the contact on the vibrator 155 works, and a magnet for operating the vibrator.

8. The combination of the bed-plate, the 160 magnet, the screw-threaded disk on which the magnet is mounted, its encircling screw- 165 threaded adjusting-ring, and the bolts H².

9. The combination of the adjustable elec- 170 tric contact-screw, the split block in which it 175 works, and a clamping device for clamping the split block upon the screw to hold it in its 180 adjusted positions.

In testimony whereof I have hereunto sub- 185 scribed by name.

FRANK B. COLMAN.
